Patented Dec. 15, 1914.

UNITED STATES PATENT OFFICE.

ALEX H. JAHNSON, OF HICKSVILLE, NEW YORK, ASSIGNOR OF ONE-THIRD TO
ALBERT C. RAVE, OF HICKSVILLE, NEW YORK.

SWIMMING-MACHINE.

1,120,720.

Specification of Letters Patent. Patented Dec. 15, 1914.

Application filed November 4, 1913. Serial No. 799,181.

To all whom it may concern:

Be it known that I, ALEX H. JAHNSON, a citizen of the United States, residing at Hicksville, Long Island, in the county of 5 Nassau and State of New York, have invented certain new and useful Improvements in Swimming-Machines; and I hereby declare that the following is a full, clear, and exact 10 description thereof, reference being had to the accompanying drawings, which form part of this specification.

This invention is a novel pleasure swimming apparatus, also capable for use as a life saving device, and its object is to provide 15 a very light portable buoyant raft or float which will support a person in the water, and is provided with manually operable means by which it can be propelled through the water at considerable speed; and when 20 not in use the device can be folded readily and transported or carried by a person from place to place or may be stored out of the way.

In the accompanying drawings I have 25 illustrated a practical embodiment of the invention and will describe same in detail so as to enable the invention to be readily understood, although I do not consider the invention restricted to the specific form and 30 construction of parts shown in the drawings, as changes may be made in details thereof within the scope of the invention.

In said drawings:—Figure 1 is a plan view of the apparatus extended and in condition 35 for use. Fig. 2 is a vertical longitudinal sectional view on line 2—2, Fig. 1, the manner of using the device being indicated in dotted lines. Fig. 3 is a transverse section on line 3—3, Fig. 1; indicating the folded 40 position of the floats in dotted lines. Fig. 4 is a detail section on line 4—4, Fig. 1.

The apparatus comprises a pair of parallel floats 3 and a central keel-board 1, which may be of wood or any other suitable material.

To the opposite ends and upper edge of this keel-board are attached standards 1^a, to the upper ends of which are pivotally connected oppositely extending transversely disposed arms 2, which may be provided with split clamps or rings 2^a adapted to embrace the floats 3. Each float is preferably made of a light hollow metal cylinder and pointed at each end as shown; such floats have suf-

ficient buoyancy to support themselves and 55 the other portions of the apparatus in the water, and also to support the weight of a person sitting or standing on the keel-board between the floats; or upon a seat-board placed across the floats. The floats are held 60 in longitudinal alinement and parallel with each other and with the keel-board, and they may be adjusted to different positions and held in such position by means of links 2^b pivotally connected to the arms 2 and to 65 slides 1^b on standards 1^a as shown; and these slides 1^b can be secured in any position on the standards by means of wing or thumb nuts 1^c as shown; or in any other suitable manner. When the apparatus is to be transported the floats are moved down close to the 70 keel-board, as indicated in dotted lines in Fig. 3; but when the apparatus is to be used they are raised and separated as indicated in full lines in the drawings.

Upon the keel-board 1 is mounted an adjustable seat 4 on which a person may sit astride; and this seat may be pivotally mounted at 4^a upon a yoke member 4^b that can be adjustably secured to the keel-board 80 by any suitable means; as for instance a bolt 4^c adapted to engage in one of a series of openings 4^d in the keel-board, so that said seat can be adjusted to suit the user of the apparatus.

The rear portion of the keel-board is preferably deepened as shown at 1^d, and onto opposite sides of this portion of the keel-board are secured reciprocating propelling devices, comprising parallel guide rods 5 upon which are slidably mounted frames 5^a of any suitable construction, as shown such frames have eyes 5^b engaging rods 5.

Each frame 5^a is provided with an outwardly projecting foot engaging push portion 5^c which may have a loop or strap 5^d attached thereto to support the foot of the user, as indicated in Fig. 2. To each frame 5^a is pivotally attached a blade or paddle 6, which is preferably made of aluminum and is loosely hinged to the frame, as shown, so that when the frame 5^a is moved forward the blade 6 will by the action of the water, swing back parallel with the keel-board; but if the frame is moved backward the action 105 of the water will cause the blade to assume a position perpendicular to the keel-board, as indicated at the upper side of Fig. 1, and

thus will exert its full surface pressure against the water. The push-portions 5^c arrest and support the blades when they are in extended position, as indicated at the upper side of Fig. 1.

The opposite frames 5^a may be connected by any suitable means so that when one is moved backward the other is automatically drawn forward. As shown this is accomplished by means of a rope or cord 6^e attached to the frames at its opposite ends and passing through an opening 1^b in the keel-board, in which opening is preferably placed a pulley 6^e to prevent friction or binding of the cord, as it moves back and forth through said opening.

Hinged to the keel-board above the paddles are a pair of horizontally disposed rudder blades 7 which may be connected by a cord 7^b to levers 7^c pivoted at 7^a to the front of the keel-board, within reach of the operator lying or sitting upon the seat 4.

To the front end of the keel-board or frame are secured hand rests 1^f by which the operator can hold on to the apparatus.

Preferably each of the floats is provided with light longitudinal wooden bars 3^c, one at top and one at the side, as shown, which serve as buffers or fenders to prevent damaging the floats by contact or collision with other bodies in the water.

If desired a small mast 8 can be rigged upon the apparatus, through an eye 8^f attached to the front standard, the bottom of the mast being stepped in a socket 8^b in the upper side of the keel-board. Said mast may be provided with a sail S and the sail control ropes s can be fastened to a ring 8^e on the rear standard, as indicated in Fig. 2.

When using the sail the operator may sit upon a light board or seat 9 placed across and between the pontoons as indicated in the drawings. The machine is intended to be used for a pleasure craft or amusement device, by bathers; and in using it the operator places the machine in the water and takes his position on the seat 4; the operator will have a standing or sitting position in the water, being practically submerged;

and when he desires to propel the machine he operates the blades with his feet by placing his feet against the foot portions 5^c and alternately pushing the frames backward; the blades connected to said frame opening out perpendicular to the keel when the frames are pushed backward, as shown in the upper side of Fig. 1, and the full force of the push is exerted to propel the machine through the water; and while one blade is pushing the apparatus the opposed paddle blade is closed as indicated at the lower side of Fig. 1 and is drawn forward. The blades or paddles automatically open and close as they are moved backward or forward by the rider or swimmer, and he can

propel himself through the water rapidly and enjoy the sensation of swimming with safety.

What I claim is:

1. In a swimming machine the combination of a keel-board, floats connected therewith, and propelling devices connected to said keel-board; with horizontal rudders attached to said keel-board above the propelling devices. 75

2. In a swimming machine the combination of a keel-board, floats connected therewith, and reciprocatory blades slidably connected to said keel-board and adapted to be operated manually; with horizontal rudders 80 attached to said keel-board, and means for operating said rudders from the front of the machine.

3. In a swimming machine the combination of a keel-board, floats connected therewith, and reciprocatory blades slidably connected to said keel-board adapted to be operated by the rider; with horizontal rudders attached to said keel-board above the propelling devices, and means for operating 90 said rudders from the front of the machine. 85

4. A swimming machine comprising a central keel-board, floats on opposite sides of the keel-board, reciprocatory frames slidably attached to opposite sides of the keel-board and hinged blades attached to said frames; with horizontal rudders attached to said keel-board, and means for operating 95 said rudders.

5. A swimming machine comprising a central keel-board, floats on opposite sides of and parallel with the keel-board connected therewith, a seat on said keel-board, and propelling means in rear of said seat adapted to be operated by a person lying 100 astride the keel-board; with horizontal rudders attached to said keel board above the propelling devices, and means for operating said rudders from the front of the machine. 10

6. In a swimming machine the combination of a keel-board, floats attached to said keel-board to suspend the same in the water, reciprocatory frames slidably attached to opposite sides of the keel-board, and propelling devices attached to said frames, said frames being adapted to be reciprocated by the feet of a person upon the seat; with horizontal rudders attached to said keel-board above the propelling devices, and means for operating said rudders from the front of the machine. 11

7. In a swimming machine the combination of a keel-board, floats adjustably attached to opposite sides of said keel-board 11 adapted to suspend the same in the water below the floats, hand rests at the front of the keel-board, reciprocatory frames slidably attached to opposite sides of the keel-board, and propelling devices attached to

said frames, said frames being adapted to be reciprocated by the feet of a person astride the keel board.

8. In a swimming machine the combination of a keel-board, a pair of floats on opposite sides of said keel-board adjustably attached thereto and adapted to suspend to same in the water below the surface, a seat mounted on said keel-board, reciprocatory frames slidably attached to opposite sides of said keel-board in rear of the seat, and

blades hingedly attached to said frames; said frames being adapted to be reciprocated by the feet of a person upon the seat astride the keel-board.

In testimony that I claim the foregoing as my own, I affix my signature in presence of two witnesses.

ALEX H. JAHNSEN.
